UNITED STATES PATENT OFFICE.

IRA A. MANN, OF PITTSBURGH, PENNSYLVANIA.

PLUMBING-FIXTURE.

1,089,776.

Specification of Letters Patent. Patented Mar. 10, 1914.

Application filed May 13, 1913. Serial No. 767,304.

To all whom it may concern:

Be it known that I, IRA A. MANN, a citizen of the United States, residing at Pittsburgh, in the county of Allegheny and State of Pennsylvania, have invented certain new and useful Improvements in Plumbing-Fixtures, of which the following is a specification.

The invention relates to plumbing fixtures, and particularly to the means for supporting the bowls pertaining to closets, urinals, sinks, and the like from side walls. The invention has for its objects, the provision of means tending to give a more secure support for the bowls and remove the strain of supporting the bowl from the partition; and the provision of supporting means including the piping whereby the thickness of the partition carrying the bowl may be reduced to a minimum. Certain embodiments of the invention are illustrated in the accompanying drawings, wherein—

Fig. 1 is a vertical section through the preferred embodiment of my invention, Figs. 2 and 3 are enlarged details of certain parts of the construction illustrated in Fig. 1, Fig. 4 is a side elevation taken at right angles to the view of Fig. 1, the bowls being removed and a portion of the face of the partition removed. Figs. 5, 6, and 7 are detail, plan, end elevation, and side elevation views of a portion of the wall supporting framework, Fig. 8 is a bottom view of one of the standards for the wall supporting framework, Fig. 9 is a plan view of one of the clamping or holding members for the horizontal soil pipe, Figs. 10 and 11 are detail sectional views of the holding means at the upper edge of the shelf of the bowl, Fig. 12 is a vertical section through a modified type of construction, Fig. 13 is a vertical section through another type of construction wherein the bowl to be supported is a sink, Fig. 13^a is a detail of the bracket used in the construction of Fig. 13, Fig. 14 is a front elevation showing the general arrangement of a battery of closets, Figs. 15 and 16 are vertical sections through modified forms of wall supporting framework and pipe clamping means. Fig. 17 is a vertical section through a partition showing the arrangement of the piping where two

bowls are supported in opposition to each other, Figs. 18, 19, and 20 are plan, side elevation, and front elevation views respectively of the fittings employed with the construction of Fig. 17, and Figs. 21 and 22 are views of a urinal fitting.

The construction involves throughout the idea of supporting wall bowls or plumbing fixtures of any kind from the piping in the wall or partition in such manner that the strain of sustaining the weight of the bowls is removed from the wall or partition. In cases where there are a plurality of bowls all leading or attached to the same horizontal soil pipe, such arrangement imposes a great strain upon the horizontal pipe, tending to not only move it from its position, but also to rotate it upon its axis. One of the objects of my invention is to properly support the horizontal soil pipe so that it cannot turn or move under the weight of the plurality of bowls, but at the same time so arranged that it may give in any direction under the expansive strains incident to changes of temperature in the piping. Another object of the invention is to so support the partition in which the piping lies that the weight of the partition will assist in supporting and maintaining the horizontal piping in position. Another idea involved in my construction is the construction of the fittings and framework in such a manner that a minimum amount of space is required for the piping, to the end that the partition carrying the piping may be reduced to the least possible thickness.

In carrying out my invention in its preferred embodiment the bowls are suspended from the piping in the partition so as to take both the tension and the thrust off of the partition, and the weight of the partition itself is carried by the framework clamping the horizontal soil pipe, so that the weight of the partition assists in maintaining the pipe supporting framework and the piping carried thereby in fixed position, regardless of the strains imposed thereon.

Referring to Figs. 1, 2, 3, and 4, 1 is one of a plurality of bowls, a number of which are indicated in Fig. 4, which may be supported against a wall or partition; 2 is a horizontal soil pipe to which are connected

the plurality of bowls by means of the fittings 3 extending upwardly and laterally as indicated in Fig. 4; and 4 are the tile or brick from which the partition or wall is built up.

The horizontal pipe 2 is held against rotation about its axis by means of a pair of opposing clamp members 5, 5, whose ends fit removably into perforations 6, 6, in the vertical standards 7, 7. As indicated in Fig. 10 clamps 5, 5, engage lugs 7, 7, carried by the horizontal pipe or by the fittings on such pipe, so that the pipe is securely held against rotary movement. By reason of the 15 plurality of holes 6, 6, the clamps 5, 5, can be adjusted to any desired height, depending upon the position of the horizontal pipe, and the standards 7, 7, may be adjusted toward and from each other by reason of the fact that the feet 8, 8, thereof (Fig. 8) extend past each other and are each provided with a plurality of holes 9 by means of which the parts may be held in any desired position of adjustment by 20 means of the bolts 10. The feet of the members 7, 7, rest upon the top of the fire-proof arch, or upon any desired supporting means in the floor, depending upon the type of building construction to which the apparatus is applied. The upper ends of the standards 7, 7, carry the rails 11, 11, such rails being in the form of T-irons with their vertical flanges slotted as indicated at 12, 12 (Fig. 7), such slots 12, 12 receiving the bolts 35 13, 13 carried by the upper ends of the standards, so that the standards may be positioned longitudinally to suit conditions. The ends of the rails or members 11, 11, are turned in as indicated at 13', 13' (Fig. 5) 40 and are provided with a plurality of bolt holes 14 through which securing bolts may be passed, this arrangement providing for an adjustment of the rails 11, 11 toward and from each other to suit partitions of varying thickness. The main portion of the partition consisting of the hollow tiles or bricks 4 is mounted upon the tops of the rails 11, so that the entire weight of the partition is carried by the standards 7, 7. This arrangement insures that the standards and the pipe 2 carried thereby shall be very securely maintained in position; although the pipe 2 may move slightly upward and axially without throwing any strain upon the supporting means, such capability being due to the lost motion connections between the clamps 5, 5 and the lugs 7, 7. Bolts 5 may be employed if desired, to give the clamps 5 greater security (Fig. 9).

60 The thrust of the bowl below the outlet connection is removed from the partition by the use of a pair of levers 15, 15 which bear at their lower ends 16 upon the face of the bowl shelf. These levers 15, 15 are pivoted 65 upon lugs 17, 17 at the sides of the fitting

3, and their upper ends are adjustable in and out by means of the nuts 18, 18 threaded upon the rods 19, 19. Around the piping member 20 is a collar composed of the parts 21 and 22 (Fig. 2), such parts being held together by means of the ends of the threaded rods 19 which fit over their ends. The rods 19 are also threaded internally and carry the tension rods 25, 25. As indicated in Figs. 10 and 11, the ends of these rods 25 extend through slots 26 in the shelf of the bowl, and through slots 27 in the hinged members 28. Washers 29 extend across the slots 27 and support the heads 30 of the rods 25. These rods 25 thus take the tension strains imposed by the weight of the bowl, and by reason of the slots 26 and 27 the piping 3 when moved up and down by expansion is free to move the bowl vertically without strain or injury, since the washers 29 are free to reciprocate vertically.

By reference to Fig. 1 it will be noted that the horizontal leg of the fitting 3 is set in so that the shoulder 32 approaches close to the axis A of the horizontal pipe 2. Also that the portion 33 of the fitting is dished or extended away from the shoulder 32 so as to compensate for the setting of the horizontal length 31 of the fitting to the left. By this arrangement an opening in the clear at B equal to the diameter of the fitting 3 is maintained, and at the same time the wall need only be given a thickness sufficient to accommodate the pipe 2. This could not be done with the ordinary fitting wherein the horizontal leg of the fitting corresponding to the leg 31 projects much farther to the right and in which the wall opposite the horizontal pipe and corresponding to the wall 33 is located much farther to the right. In other words, the applicant by setting the leg 31 into the fitting and dishing the opposite side of the fitting reduces the thickness of wall of the building necessary to accommodate the fitting, without contracting the opening through the fitting.

In Fig. 12 a modified structure is illustrated, the primary distinctions in this apparatus over the apparatus of Fig. 1 being in the means for preventing the rotation of the horizontal soil pipe; in the character of the fitting corresponding to the fitting 3; and in the means for adjusting the levers for taking the thrust of the bowl. In this construction the horizontal pipe 2' is held by a pair of clamping members 34 and 35 which engage a fitting on the pipe 2', the end of one of the members being extended as indicated at 36 and lying in the concrete of the floor. The interior surface of the clamping members 34 and 35 is corrugated to give a better gripping engagement with the fitting, and if desired, the fitting may be correspondingly corrugated. The fitting 37 is in the form of a T and is connected to the

L 38 by means of the pipe 39, three parts being employed in this type of construction to take the place of the single fitting 3 of the construction of Fig. 1. As in the other type of construction the rear wall of the L 38 is dished as indicated at 40, and the horizontal leg 41 of the L is set to the left, so that the distance between the interior surfaces of the walls of the partition need be only sufficient to accommodate the lower flange 42 of the L 38. At the same time the diameter C is kept substantially the same as that of the interior of the pipe 39. With the ordinary L now in use the right hand end of the leg 41 would extend a considerable distance farther to the right, requiring that the opposing wall of the partition be set to the right, while the left hand side of the L in such ordinary construction would occupy a position no farther to the right than in the applicant's construction and required partition of greater thickness.

In this construction of Fig. 12 the tension imposed upon the rods 43 is taken by a pair of blocks 44 carried by the collar 45, such collar having a pair of downwardly projecting lugs 46. These lugs 46 carry screws 47 by means of which the levers 48 pivoted on the L 38 may be adjusted to make their lower ends 49 properly engage the base of the bowl below the connection 50.

Fig. 13 illustrates the method employed in applying the invention to the support of a sink. In this construction a sink 51 is supported upon a plate 52 carried by the wall 53, the plate 52 being supported from the piping as hereinafter described. The back of the sink is provided with a hook portion 54 which fits over the top of the plate. Behind the wall 53 is the plate 55 of the skeleton outline shown in Fig. 13^a, with its lower edge at 56 resting on the outlet connection 57. The plate is provided with slots 58 and 59 which are engaged by the bolts 60 extending from the plate 52. The plate 55 is itself securely supported upon the pipe 61 by means of the collars 62 secured to the plate by means of the bolts 63 (Fig. 13^b).

Fig. 14 illustrates a construction similar to that of Fig. 4, the partition being removed to more clearly disclose the piping. Insofar as the connection from the bowls 1^a to the horizontal pipe 2^a are concerned, these connections are similar to the ones illustrated in Fig. 12, the three fittings 38, 39, and 57 being used instead of the single connection 3 of Fig. 4. The vent pipes 64 are all attached to a common horizontal vent pipe 65 which leads into the vertical vent pipe 67. The framework for supporting the partition, involving the standards 6 and rails 14 are similar to those shown in Fig. 4. In this case the feet of the standards 6 rest upon the supporting tile 68.

Fig. 15 illustrates another method of sup-

porting the partition 69 and for preventing the rotation of the horizontal soil pipe 2^a. The partition rests upon a T-iron 70 bolted to the clamping members 71 and 72 which in turn are supported upon the T-iron leg 73, the clamping members being bolted together in the manner illustrated and being adapted to prevent the rotation of the pipe by reason of the lugs 74 and 75 on the pipe 2^a.

The construction of Fig. 16 is similar to that of Fig. 15, the primary difference residing in the fact that the clamping members 76 and 77 for engaging the pipe 2^a are of somewhat different form, being provided with two holding bolts at the upper end instead of one. The partition consists of metal lath 78 and angle irons 79 bolted at their lower ends to the section 80 and secured above the pipe to the section 80. The clamping members are secured to the sections 80 and 80^a.

Figs. 17, 18, 19, and 20 illustrate the fitting employed where bowls 81 and 82 come opposite each other on the same partition 83 (Fig. 17), the fitting employed for connecting the bowls to the vertical pipe 84 being similar in principle to that illustrated in Figs. 1 and 12, but being a double fitting instead of a single fitting. By reference to Figs. 18 to 20 it will be seen that the fitting has two vertical legs 85 and 86 for connection separately to vent pipes, two horizontal legs 87 and 88 for connecting to the couplings supporting the bowls, and a single outlet leg 89, which leg is connected to the vertical piping 84 (Fig. 17). By reference to the dotted lines in Fig. 19 it will be seen that the two horizontal legs 87 and 88 are set in, so that the outer faces of the legs 87 and 88 are gotten as close as possible to the center line A of the fitting and do not extend past the hub 89 of the hub on outlet pipe 84, thus following the idea involved in Figs. 1 and 12. Similarly the walls or faces 90 and 91 opposite the legs 87 and 88 respectively are dished or flared back so as to give the requisite amount of space between such walls and the inner ends 92 and 93 of the said legs. In this manner the over-all dimension B is reduced to a minimum, established by the diameter of pipe 84, so that the thinnest possible partition may be employed, and this without restricting the diameter of the passages through the fitting. A partition 92 (Fig. 20) serves to partially separate the two chambers in the fitting and prevent the operation of the closet on one side affecting the contents of the other closet. The separate vents 85 and 86 prevent the siphonage of both fixtures when only one is operated.

Figs. 21 and 22 illustrate the connection employed when the apparatus is a urinal. 93^a is the outlet pipe having a hub 94 lying between the walls 95 and 96. By the use of the outlet connection 97 having the reverse 130

downward curve 98, a free and unobstructed discharge is possible without the necessity of spacing the walls 95 and 96 any farther apart than is necessary to receive the hub 94 of the pipe 93.

5. What I claim is:

1. In a building structure, the combination with a horizontal soil pipe and vertical piping connected thereto and lying within a 10 partition, of a wall bowl abutting the partition, connections whereby the said piping carries the bowl, and connections between the said horizontal pipe and the building structure in which the pipe is located, for 15 preventing the rotation of the horizontal pipe about its axis.

2. In a building structure, the combination with a horizontal soil pipe and vertical piping connected thereto and lying within a 20 partition, of a wall bowl abutting the partition, connections whereby the said piping carries the bowl, and means secured to the horizontal pipe and coöperating with the building structure for preventing the rotation 25 of the horizontal pipe about its axis.

3. In a building structure, the combination with a horizontal soil pipe and vertical piping connected thereto and lying within a partition, of means supporting the partition, 30 a wall bowl abutting the partition and communicating with the vertical piping, connections whereby the said piping supports the bowl, and connections between the horizontal pipe and the said means supporting the 35 partition for preventing the rotation of the horizontal pipe about its axis.

4. In a building structure, the combination with a horizontal soil pipe and vertical piping connected thereto and lying within a 40 partition, of a metal framework supporting the partition, a wall bowl abutting the partition and communicating with the vertical piping, connections whereby the said piping supports the bowl, and connections coöperating 45 with the said framework whereby the horizontal pipe is prevented from turning.

5. In a building structure, the combination with a horizontal soil pipe and vertical piping connected thereto and lying within a 50 partition, of a metal framework supporting the partition, a wall bowl abutting the partition and communicating with the vertical piping, connections whereby the said piping supports the bowl, and connections coöperating 55 with the said framework whereby the horizontal pipe is prevented from turning, the said framework being adjustable as to width to suit partitions of varying thickness.

60 6. In a building structure the combination with a horizontal soil pipe and vertical piping connected thereto and lying within a partition, of a metal framework supporting the partition, a wall bowl abutting the 65 partition and communicating with the ver-

tical piping, connections whereby the said piping supports the bowl, and connections coöperating with the said framework whereby the horizontal pipe is prevented from turning, said connections being made in two 70 parts and adjustable toward and from each other to suit partitions of varying thickness.

7. In a building structure, a partition, vertical piping therein, a wall bowl having an outlet communicating with the vertical 75 piping, a tension connection between the piping and the bowl above the said outlet, a lever pivoted on the said piping and bearing against the bowl below the said outlet, and means above the said outlet for adjusting so the upper end of the lever away from the bowl.

8. In a building structure, a partition, vertical piping therein, a wall bowl having an outlet communicating with the vertical 80 piping, a lever pivoted to the said piping and bearing against the bowl below the said outlet, and means above the said outlet for adjusting the upper end of the lever away from the bowl.

9. In a building structure, a partition, vertical piping therein, a wall bowl having an outlet communicating with the vertical piping, a tension connection between the piping and the bowl above the said outlet, a 90 lever pivoted on the said piping and bearing against the bowl below the said outlet, and means carried by the said tension connection for adjusting the upper end of the lever away from the bowl.

10. In a building construction, a partition, vertical piping therein provided with a lateral inlet L, a wall closet having an outlet connected with the said L, a lever pivoted to the said L and bearing against the 105 bowl below the said outlet, and means for adjusting the upper end of the lever away from the bowl.

11. In a building construction, a partition, outlet piping in the partition, a fitting 110 forming part of such piping and having an upright leg and a horizontal leg, a wall bowl having an outlet communicating with the horizontal leg, the said horizontal leg being set into the vertical leg so that its inner end 115 lies to the rear of the interior front surface of the upright leg farther down, and the interior of the upright leg opposite the end of the horizontal leg being dished so that it lies to the rear of the interior rear surface 120 of the upright leg farther down.

12. In a building construction, a partition, outlet piping in the partition, a fitting forming a part of such piping and having a downwardly extending leg and a horizontal 125 leg, a wall bowl having an outlet, and a connection extending from such outlet to the horizontal leg, the downwardly extending leg having its center-line opposite the end of the horizontal leg curved first to the rear 130

so that it lies to the rear of the center-line of the partition, and then back to the front, and the inner end of the horizontal leg being set into the fitting so that its inner end lies nearer to the center-line of the partition than the interior of the pipe at the lower portion of the downwardly extending leg.

In testimony whereof I have hereunto signed my name in the presence of the two subscribed witnesses.

IRA A. MANN,

Witnesses:

ARCHWORTH MARTIN,

LETITIA A. MYERS.
